UNITED STATES PATENT OFFICE.

EDWARD COULSON, OF LOS ANGELES, CALIFORNIA.

PROCESS OF AND MEANS FOR PERMANENTLY WAVING HAIR.

Application filed February 26, 1926. Serial No. 90,729.

My invention relates to a novel process of and means for permanently waving and treating hair.

Little difficulty is experienced in waving 5 hair so that the wave will remain in the hair for a very considerable period of time and when done the wave is put in as close to the scalp as possible. The hair grows fairly rapidly, the average normal rate of growth 10 being perhaps about one-half inch per month. In the course of a few months there is a substantial growth of new unwaved hair between the scalp and that portion previously waved. In the process of per- 15 manently waving hair a softening agent, such as borax in powdered or crystal form, is used in the presence of steam or vapor to condition the hair so it can be distorted from the natural formation to the desired shape. 20 It is well known that the process of permanently waving hair cannot be carried out on the same hair more than once without effecting considerable injury to the hair by making it brittle and easily broken; consequent- 25 ly, it is usually necessary to permit the hair to grow sufficiently to yield an entirely new growth of hair where the wave is desired before a new permanent wave can be safely put in, and during this time more and more 30 of the straight new growth of hair appears which must be waved frequently with a curling iron or other means to make it harmonize in appearance with the old growth of permanently waved hair. It is one of the 35 objects of my invention to provide a novel process of permanently waving hair which is carried out in such a way that a permanent wave can be put in the new growth, regard- 40 less of its length, whenever desired and without any injurious effects to the older growth of the previously, permanently waved hair. To this end the hair, includ- 45 ing the new growth and the older growth previously permanently waved, is wound on a curler in the ordinary way; a saturated pad carrying a hair softening agent in quantity and over an area thereof to suit the new growth of unwaved hair is then placed about the hair on the curler in such manner that 50 the area carrying the hair softening agent is adjacent the new growth of unwaved hair only; then a wrapper of moisture or vapor confining material is placed about the pad and finally the whole is subjected to the ac- 55 tion of heat. Frequently the hair grows more rapidly on some parts of the head than

on other parts and my new process makes it entirely possible to use the correct amount of hair softening agent on the proper area of the pad to suit best the needs of the par- 60 ticular tress of hair on the curler to which the particular pad is to be applied.

It is another object of my invention to im- 65 prove the condition and appearance of the hair, particularly the old growth of perma- 70 nently waved hair, at the same time the new growth is being permanently waved and to this end I preferably saturate the pad with a solution for treating the hair consisting of ingredients suitable for the purpose. The 75 steam or vapor generated by the action of the heat on the solution absorbed in the pad not only produces the desired chemical re- 80 action with the hair softening agent for permanently waving the new growth of hair but it also improves the condition and ap- 85pearance of the entire tress of hair and the effect is particularly noticeable on the older growth of the previously, permanently waved hair.

The pads commonly used heretofore in connection with hair waving means have been objectionable because they have retained excessive moisture which necessitates an ex- 90cessive amount of time for completing the hair waving operation and increases the like- 95lihood of moisture reaching the scalp and causing discomfiture, if not considerable pain. The old pads are objectionable also because of the fact that their structure is 100 such that they are incapable of continued use, or of giving efficient service in making more than one curl, thus the cost of the pads has been high. Additional objects of my invention are—to provide a pad capable of 105 retaining just enough moisture for generating the proper amount of steam or vapor necessary for curling the hair, thereby eliminating the danger of any excess moisture reaching the scalp, and also shortening the 110 time for the hair waving operation; to pro- 115vide a pad wherein the composition and construction are such as to permit of its efficient use in making several curls, thereby reducing the cost of the waving operations; and to construct a pad that will be inexpensive to manufacture and handle in use, and, at the same time, efficient and practical in its operation.

The covering tube heretofore used in con- 110nection with the pad for confining about the hair the steam or vapor generated, is

stiff and has to be moistened sufficiently on the end adjacent the scalp to enable it to be folded or crimped and fastened closely about the tress of hair to prevent the escape of moisture or steam to the scalp. The use of such tubes and moistening the ends thereof are objectionable for various reasons, for example the tubes come only in stock sizes and oftentimes they do not fit about the particular tresses of hair to the best advantage; if the ends of the tubes are not moistened enough, the tubes are too stiff to be crimped tightly and properly about the hair to prevent leakage, thus causing burns to the scalp; and if the ends of the tubes are moistened too much, the material of the tubes becomes weakened to such an extent that the strings or clips used to fasten the tubes closely about the hair are likely to cut through the tubes, thereby causing leakage and burns to the scalp. Further objects of my invention are—to provide an arrangement wherein the tube, as such, will be eliminated and instead, an outer wrapper in sheet-like form of suitable material, used whereby the pad and wrapper can be readily arranged to the best advantage around the particular tress of hair under treatment; and to provide an arrangement of the pad covering, inner and outer wrapper such that sufficient moisture will be applied automatically to the scalp-end of the outer wrapper to permit it to be fastened tightly about the tress of hair under treatment.

35 A preferred embodiment of the invention is illustrated in the accompanying drawings and hereinafter specifically described. That which I believe to be new and desire to secure by Letters Patent is set forth in the appended claims.

In the drawings,—

Fig. 1 is a vertical sectional view of hair waving means embodying the principles of my invention and suitable for carrying out my improved process;

Fig. 2 is a perspective view illustrating the steps of treating the pads preparatory to the waving operation;

Fig. 3 is a face view of the pad, inner wrapper and outer wrapper showing the parts assembled in their relative positions preparatory to receiving the curler and hair, and to being wound thereon, certain of the parts being broken away to show more clearly the relative positions of the various elements; and

Fig. 4 is a transverse sectional view, taken as indicated on the line 4—4 of Fig. 3.

As illustrated in the drawing, the tress of hair to be waved is wound in the ordinary manner on a curler 6 and secured thereto at its outer end and also at its inner end, or the scalp end, by strings or other suitable fastening means 7 and 8, respectively.

65 To supply the moisture necessary for the

hair waving and treating operation, a pad 9 is provided which comprises a pliable, absorbent, fibrous, moisture-retaining body 10 of suitable material, preferably, asbestos pulp. A covering 11, preferably of loosely woven fabric such as cheese cloth, gauze or the like, is folded around the body 10 and has its overlapping edges secured to the body by a line of stitching 12 as clearly shown in Figs. 3 and 4. The relative sizes and positions of the covering 11 and the body 10 preferably are such that one open end of the covering will be substantially even with one edge of the body, as indicated at 13 in Fig. 3, while the opposite end of the covering extends beyond the adjacent edge of the body, as indicated at 14, for purposes herein-after described.

For confining the steam or vapor generated from the moisture contained in the pad about the hair under treatment, an inner wrapper 15 is provided, which comprises preferably a sheet of suitable moisture proof material 16 such, for example, as cellophane glass, and a sheet of paper of suitable weight and texture preferably folded upon itself over the material 16 to form the plies 17 and 18 on opposite sides of said material. The material 16 preferably is secured to the sheet of paper adjacent its folded portion by a suitable adhesive.

To aid further in confining the steam or vapor about the hair, a sheet-like covering member or outer wrapper 19 is preferably employed. This wrapper is of any suitable material such as paper of a strong texture capable of being wrapped with and of holding the inner wrapper and pad firmly about the hair to be curled. The relative sizes and positions of the pad and the inner and outer wrappers are shown in Fig. 3. It will be noted that a portion of the outer wrapper overlies the extended pad covering portion 14. That part of the outer wrapper overlying the pad covering portion 14 absorbs moisture therefrom thus conditioning the scalp-end of the wrapper to be crimped and secured with the extended gauze portion 14 closely around the tress of hair in a manner to prevent escape of any steam from that end of the tube-like structure thus formed. The wrappers are preferably secured together in the desired relationship, by an adhesive substance disposed as indicated by the heavy line 20 in Fig. 4.

In carrying out the process of my invention, the head of hair to be waved is divided into tresses which are wound on the curlers and fastened thereto, respectively, in the usual manner, protective shields 21 of suitable material such as felt being placed over the respective tresses of hair close to the scalp as shown in Fig. 1. Ordinarily from 25 to 40 curlers are used on a head of hair. The pads 9, equal in number to the number

of curlers used on the head of hair to be waved, are placed in a stack 22 in a vessel 23 and a liquid solution is poured thereover to saturate thoroughly each individual pad 5 in the stack. The solution used by me for saturating the pads preferably contains oils, ammonia and other ingredients useful in restoring the luster and vitality of the hair. After the pads have been thoroughly saturated 10 with the hair treating solution, they are removed from the vessel, compressed in the hands to eliminate the excess liquid and are disposed in stacked relation in some place convenient for the operator. A pad is then taken up by the operator and a proper quantity of a suitable hair softening agent, such as borax in crystal or powdered form, is externally applied to a preselected area thereof as shown at the right of Fig. 2. The 15 pad is then placed on the inner and outer wrappers as shown in Fig. 3 and these elements are then wound around the tress of hair on a curler substantially as shown in Fig. 1. The moisture present in the extended pad covering portion 14 supplies sufficient moisture to that portion of the outer wrapper 19 which overlies the portion 14 to permit said portion of the outer wrapper to be readily crimped with the portion 14 closely 20 about the tress of hair adjacent the scalp; said portions are secured tightly about the tress of hair by any suitable fastening means, a clip 24 of the construction described in my Patent No. 1,328,422, being shown for 25 this purpose in Fig. 1. The outer end of the sheet of cellophane glass 16 together with the outer end of the wrapper 19 are crimped over the outer end of the curler in the desired manner to control the confinement of 30 the steam or vapor about the hair. This is a matter that can be regulated by the operator as seems most desirable. At 25 on the inner face of the outer wrapper a quantity of adhesive is applied so that the corner of 35 the wrapper can be drawn around and secured to the body of the wrapper in the desired position. After the pads and wrappers have been applied to the respective tresses of hair in the manner described, the 40 heaters are applied thereover in the usual manner. One form of heater 26 is shown in Fig. 1 in position about the wrapped tress of hair. In Fig. 1 of the drawing no attempt has been made to show all the respective 45 laminations of the pad and the inner and outer wrappers as these elements would actually appear when rolled around the hair and the curler as above described. The reference characters have been applied in Fig. 1 50 to the several elements in the same manner as they have been applied in Fig. 3.

It will be apparent that my process is readily adapted for initially putting in a permanent wave to a head of hair, in which 55 case the hair softening agent will be applied to substantially the entire inner surface of the pads 9 so that all the hair on the curler will be waved. The advantages of my improved process are most apparent in permanently waving the new growth on a head of 60 hair which has been permanently waved at some prior time. This will be clearly understood if we assume that the hair on the curler 6 embraced by the bracket 27 is of new growth and unwaved and that the portion 65 embraced by the bracket 28 is of older growth and has been permanently waved at some previous time. It will be noted that approximately one-half the hair on the curler 6 is of new growth. As heretofore 70 explained, it is highly desirable to avoid re-treating the hair which has been permanently waved at some previous time with the hair softening agent. The operator can readily distinguish the new growth of 75 unwaved hair from the older growth of waved hair when the tress is wound on the curler. In applying the hair softening agent to the pad to be placed around a particular tress of hair, the operator applies the hair softening agent to the pad over such an area thereof that, when the pad is placed about the wound hair on the curler, only that portion 80 of the pad carrying the hair softening agent will be disposed next to the new growth of 85 unwaved hair. In this way it will readily be seen that by the use of pads adapted to have the hair softening agent externally applied thereto, the pads may be prepared in a manner best suited for the respective 90 tresses of wound hair. It is well known that the hair grows more rapidly on some parts of the head than on other parts and this fact is taken into consideration by the operator in applying the hair softening 95 agent to the pads for the respective tresses of hair. Furthermore, there is considerable difference in the texture of various heads of hair. Hair of fine texture requires a larger amount of the hair softening agent to condition it properly for a permanent wave than hair of a coarser texture. Here again my new process enables an operator to take this fact into consideration in applying the proper amount of the hair softening agent 100 to the pads. It will be apparent that my process readily enables an operator to put in a wave on a head of hair which has been waved at some previous time or which is entirely straight in a scientific manner best 105 suited to the particular head of hair. The process makes it possible for a patron to have the new growth of hair waved at any time and without any injurious effects to the older growth of hair, thereby making 110 115 it possible for the patron to keep her hair dressed in the most attractive manner with practically no bother or trouble and without resorting to the use of ordinary curling irons or other make-shift devices.

The hair treating solution used in saturating the pads not only supplies sufficient moisture for producing the chemical reaction with the borax necessary for permanently waving the hair but the vapor or steam generated has a very beneficial effect on the hair and this is particularly true as to that part of the hair on the curler which has been waved at some previous time. It 10 gives the hair a lustrous appearance at the same time the hair is being permanently waved.

A pad of the construction described herein is efficient, durable and capable of carrying 15 a suitable hair treating solution for generating the proper amount of steam or vapor and for carrying a suitable quantity of the hair softening agent. The pad is highly efficient and practical for the purpose intended. It is to be noted that the pad will not disintegrate or crumble readily. It is of such a structure that it may be saturated repeatedly with a hair treating 20 solution and used for several hair waving operations. No excess moisture is carried by the pad and hence there is not an excessive amount of steam or vapor generated and the likelihood of the scalp being burned on this account is minimized. Furthermore 25 when there is not an excessive amount of vapor or steam generated the time required for putting in the wave is reduced to a minimum.

The arrangement of the inner and outer 30 wrappers makes it feasible for the operator to control the escape of the steam or vapor generated from the outer end of the tube-like structure. The arrangement is such that a tube may in effect be built around the 35 curler to suit best the particular tress of hair thereon, all of which lends itself to a scientific waving and treatment of the hair.

While I prefer to employ the form of pad 40 and the form of inner and outer wrappers illustrated in the drawing and as above described, it will be understood that I do not intend to be limited to such specific forms or structures, except only as they may be 45 specifically claimed, since it is evident that changes may be made therein without departing from the spirit of my invention.

I claim:

1. In the herein described process of permanently waving hair, the steps of winding 50 a tress of hair on a curler, saturating a pad, applying a hair softening agent externally to the wet pad, placing the pad carrying the hair softening agent around the wound hair, applying vapor or moisture confining means about the pad, and then subjecting the hair and pad to the action of heat, for the purpose specified.

2. In the herein described process of permanently waving hair, the steps of winding 55 a tress of hair on a curler, saturating a pad,

applying a hair softening agent in powdered or crystal form externally to the wet pad, placing the pad carrying the hair softening agent around the wound hair, applying vapor or moisture confining means 70 about the pad, and then subjecting the hair and pad to the action of heat, for the purpose specified.

3. In the herein described process of permanently waving a new growth of straight 75 hair without rewaving the previously waved hair, the steps of winding a tress of unwaved and waved hair on a curler, applying to a pad a hair softening agent in quantity and over an area thereof to suit the new 80 growth of unwaved hair, placing the pad around the wound hair so that the area carrying the hair softening agent is adjacent the new growth of unwaved hair only, applying vapor or moisture confining means 85 about the pad, and then subjecting the hair and pad to the action of heat, for the purpose specified.

4. In the herein described process of permanently waving a new growth of straight 90 hair without rewaving the previously waved hair, the steps of winding a tress of unwaved and waved hair on a curler, saturating a pad, applying to the wet pad a hair softening agent in quantity and over an area 95 thereof to suit the new growth of unwaved hair, placing the pad around the wound hair so that the area carrying the hair softening agent is adjacent the new growth of unwaved hair only, applying vapor or moisture 100 confining means about the pad, and then subjecting the hair and pad to the action of heat, for the purpose specified.

5. In the herein described process of permanently waving a new growth of straight 105 hair without rewaving the previously waved hair, the steps of winding a tress of unwaved and waved hair on a curler, saturating a pad, applying externally to the wet 110 pad a hair softening agent in powdered or crystal form and in quantity and over an area thereof to suit the new growth of unwaved hair, placing the pad around the wound hair so that the area carrying the hair softening agent is adjacent the new 115 growth of unwaved hair only, applying vapor or moisture confining means about the pad, and then subjecting the hair and pad to the action of heat, for the purpose specified.

6. In the herein described process of permanently waving hair, the steps of winding a tress of hair on a curler, saturating a pad consisting of a body of absorbent material having an absorbent covering which at one 125 side extends a substantial distance beyond the body, applying a hair softening agent externally to the wet pad, placing the pad carrying the hair softening agent around the wound hair with the extended portion of the 130

5 pad covering adjacent the scalp, applying an inner wrapper of vapor or moisture confining material about the body portion of the pad, applying an outer wrapper about the inner wrapper so that the edge thereof adjacent the scalp is substantially even with the corresponding edge of the pad covering, and then placing a heater about the hair, 10 pad and the aforesaid wrappers, for the purpose specified.

7. In the herein described process of permanently waving hair, the steps of winding a tress of hair on a curler, saturating a pad 15 consisting of a body of absorbent material having an absorbent covering which at one side extends a substantial distance beyond the body, applying a hair softening agent externally to the wet pad, placing the pad carrying the hair softening agent around 20 the wound hair with the extended portion of the pad covering adjacent the scalp, applying an inner wrapper of vapor or moisture confining material about the body portion of the pad, applying an outer sheet-like 25 wrapper about the inner wrapper so that the edge thereof adjacent the scalp is substantially even with the corresponding edge of the pad covering, securing the scalp-end or inner end of the outer wrapper and the extended pad covering portion closely about the hair to prevent the escape of steam or vapor, and then placing a heater about the hair, pad and the aforesaid wrappers, the outer end of the outer wrapper being secured 30 about the hair in a manner to control the amount of steam or vapor maintained about the hair during the treatment or waving process.

8. In means for waving hair, the combination of a saturated pad of absorbent material having a hair softening agent externally applied thereto and adapted to be placed about a tress of hair on a curler, and a wrapper of vapor or moisture confining material adapted to be wrapped around the pad, for the purpose specified.

9. In means for waving hair, the combination of a pad of absorbent material having a hair softening agent applied to a pre-selected portion only thereof and adapted to be placed about a tress of hair on a curler, and a wrapper of vapor or moisture confining material adapted to be wrapped around the pad, for the purpose specified.

10. In means for waving hair, the combination of a pad of absorbent material having a hair softening agent in powdered or crystal form applied to a pre-selected portion only thereof and adapted to be placed about a tress of hair on a curler, and a wrapper of vapor or moisture confining material adapted to be wrapped around the pad, for the purpose specified.

11. In means for waving hair, the combination of a pad of absorbent material satu-

rated with a hair treating solution and having a hair softening agent externally applied thereto, said pad being adapted to be placed about a tress of hair on a curler, and a wrapper of vapor or moisture confining material adapted to be wrapped around the pad, for the purpose specified.

12. In means for waving hair, the combination of a pad of absorbent material having a hair softening agent externally applied to a pre-selected portion only of the surface thereof, said pad being adapted to be placed about a tress of hair on a curler, and a wrapper of vapor or moisture confining material adapted to be wrapped around the pad, for the purpose specified.

13. In means for waving hair, the combination of a pad of absorbent material saturated with a hair treating solution and having a hair softening agent in powdered or crystal form externally applied to a pre-selected portion only of the surface thereof, said pad being adapted to be placed about a tress of hair on a curler, and a wrapper of vapor or moisture confining material adapted to be wrapped around the pad, for the purpose specified.

14. In means for waving hair, the combination of a saturated pad comprising a sheet-like body of absorbent material having an absorbent covering which at one side extends a substantial distance beyond the body, said pad carrying a hair softening agent and being adapted to be placed about a tress of hair on a curler with the extended portion of the pad covering adjacent the scalp, an inner wrapper of vapor or moisture confining material placed about the body portion of the pad, an outer sheet-like wrapper placed about the inner wrapper so that the edge thereof adjacent the scalp is substantially even with the corresponding edge of the pad covering, and means for securing the outer wrapper over the extended portion of the pad covering closely about the hair, for the purpose specified.

15. In means for waving hair, the combination of a saturated pad comprising a sheet-like body of absorbent material having an absorbent covering which at one side extends a substantial distance beyond the body, said pad carrying a hair softening agent and being adapted to be placed about a tress of hair on a curler with the extended portion of the pad covering adjacent the scalp, an inner wrapper of vapor or moisture confining material placed about the body portion of the pad, an outer sheet-like wrapper placed about the inner wrapper so that the edge thereof adjacent the scalp is substantially even with the corresponding edge of the pad covering, means for securing the scalp end or inner end of the outer wrapper over the extended portion of the pad covering closely about the hair, and means for

securing the outer wrapper at the opposite end about the tress of hair in the desired relation, for the purpose specified.

16. In means for waving hair, the combination of a saturated pad comprising a sheet-like body of absorbent material having an absorbent covering which at one side extends a substantial distance beyond the body, said pad carrying a hair softening agent and being adapted to be placed about a tress of hair on a curler with the extended portion of the pad covering adjacent the scalp, an inner wrapper of vapor or moisture confining material placed about the body portion of the pad, an outer sheet-like wrapper placed about the inner wrapper so that the edge thereof adjacent the scalp is substantially even with the corresponding edge of the pad covering, means for securing the scalp end or inner end of the outer wrapper over the extended portion of the pad covering closely about the hair, and adhesive means carried on the outer wrapper at its opposite end for securing said last-named end of the wrapper about the tress of hair in the desired relation, for the purpose specified.

17. In means for waving hair in a tubular heater, the combination of an absorbent pad adapted to be wound when wet directly

about a tress of hair, an inner wrapper of moisture-proof material wound about said pad with a small portion of the pad unwrapped adjacent to the scalp, and an outer wrapper of absorbent material wound about said inner member and the exposed portion of the pad adapted when crimped about the end portion of the pad to be moistened thereby to assist in obtaining a tight closure thereabout.

18. In means for waving hair in a tubular heater, the combination of an inner wrapper of moisture-proof material and an outer wrapper of absorbent material secured in face contact therewith with one edge projecting some little distance beyond the corresponding edge of the inner wrapper.

19. In means for waving hair in a tubular heater, the combination of a sheet of fibrous material folded upon itself, a sheet of moisture-proof material between the plies of the fibrous material, and an outer wrapper of absorbent material secured in face contact with said sheet of fibrous material with one of its edges even with the folded edge of said first named sheet and with an edge adjacent thereto projecting some little distance beyond the corresponding edge of the first named sheet.

EDWARD COULSON.
